UNITED STATES PATENT OFFICE.

WALTER JAY TREMAN, OF SHELBY, OHIO, ASSIGNOR OF ONE-HALF TO
CLARENCE BRIGHTMAN, OF SHELBY, OHIO.

PIN-SPOTTER.

No. 832,885.

Specification of Letters Patent.

Patented Oct. 9, 1906.

Application filed April 12, 1906. Serial No. 311,260.

To all whom it may concern:

Be it known that I, WALTER JAY TREMAN, a citizen of the United States of America, and a resident of Shelby, Richland county, Ohio, have invented certain new and useful Improvements in Pin-Spotters, of which the following is a specification.

My invention relates to bowling, and has for its objects the construction of a device that will afford facilities for setting the pins in proper position rapidly, uniformly, and exactly on the same spot each time they are set up.

It consists, further, in the particular construction and arrangement of the parts shown and described.

I attain these and other objects by the mechanism illustrated in the drawings, in which—

Figure 1 is a longitudinal section taken through the center of Fig. 2 and detail of operating mechanism with part of bowling-pins broken away to show end of spotting-pins inserted in aperture in bottom of bowling-pins. Fig. 2 is a top plan view of a bowling-alley, showing pins set in proper position preparatory to forcing them below the surface of the alley. Fig. 3 is a plan view of the reciprocating pin-plate. Fig. 4 is a top plan view of the operating-lever. Fig. 5 is a side view of Fig. 4. Fig. 6 is a top view of part of the operating mechanism in dotted lines. Fig. 7 is a top view of an alley, showing the operating-lever located on the side of the alley. Figs. 8 and 9 are side and end views, respectively, of the bifurcated standard. Figs. 10 and 11 show a top and side view, respectively, of the operating-lever. Figs. 12 and 13 show a side and end view, respectively, of the ring-bushing. Fig. 14 is a plan view of the operating-rod, showing bifurcated ends.

In the drawings, 1 represents an ordinary bowling-alley. In the construction of my device I prefer to form a recess 2 and inclose it with the cross-piece 3, which forms the end of the alley adjacent to the pit 4. A longitudinal aperture 5 is formed in the center of the pit 4 and communicates with the recess 2. A bushing 6, having both ends enlarged, leaving a ring portion 7 in the center, is fitted to the aperture 5. An operating-lever 8, having its end 9 preferably turned at an angle to the body portion, is pivotally journaled in

the aperture in the ring 7 of the bushing. It 55 will be observed that the bushing is so placed in the aperture 5 as to leave the angular end of the operating-lever resting on the bottom of the recessed portion of the alley, with the ends of the spotting-pins 10 lying below the 60 surface of the alley. A vertical aperture 11 is provided in the end of the pit 4, intersecting the aperture 5, into which the bifurcated lever-rod 12 is loosely fitted, with the ends 13 13 adapted to fit the flattened ends 14 of the 65 operating-lever and locking-lever 15.

A bracket 15^a is secured to the top of the back-stop 15^b and pivotally supports the locking-lever 15, which alines with and is secured to the bifurcated end of the lever-rod 70 12, affording a means of imparting an oscillating motion to the operating-lever, which in turn reciprocates the plate carrying the spotting-pins.

A plate 16, having a series of spotting-pins 75 10 securely fastened thereto, is provided and placed in the recess 2 and rests on the top 17 of the end 9 of the operating-lever 8. The spotting-pins extend into the corresponding apertures 18 in the surface of the alley and 80 when not in use lie below the surface. The bowling-pins 19 are provided with apertures 20, tapered or straight to fit loosely the end of the spotting-pins. A back-stop 21, having a recessed portion 22, is securely fastened 85 to the end of the pit.

A suitable elastic washer 23, preferably made of rubber, is inclosed in the recess 22. The aperture which is formed in the washer is made smaller in diameter than the lever- 90 rod 12 and forced thereon to provide frictional contact therewith sufficient to retain the lever-rod at any point or position of its travel at the will of the operator and retaining the spotting-pins above or below the surface of 95 the alley for the purpose intended.

The operation of my device is as follows: When it is desired to set the pins, the operator presses down on the locking-lever 15. This pivots the operating-lever in the ring-bushing, imparting an upward movement to the end which is in contact with the bottom of the plate, forcing the ends of spotting-pins which are carried by the plate above the surface in exact and uniform position preparatory to the bowling-pins being set thereon. When the pins are set, the locking-lever 15 is pulled upward, pivoting the operating-lever

and forcing the angular end 9 to lie on the bottom of the recess 2. This movement permits the plate to drop by gravity, carrying the spotting-pins below the surface of the alley. A plate 25 keeps the operating-lever in place, the end contacting therewith. To provide an indicator or guide to show when the spotting-pins are below the surface, the end of the front pin 26 of the series is made longer. When the bowling-pins are set upon the spotting-pins, the top of the front bowling-pin will be above the plane of the other pins, indicating that the spotting-pins are not below the surface of the alley. The operating mechanism can be positioned on the side of the alley or secured to the alley without recessing the bottom.

I do not confine myself to the exact arrangement or construction of the parts shown, as slight alterations can be made without deviating from the principle herein involved.

Having fully described my invention, what I claim, and desire to secure by Letters Patent, is—

- 25 1. A pin-spotting device for bowling-alleys, comprising an alley having apertures provided in one end, an angular plate having pins secured thereto and adapted to register with said apertures, a bushing, an operating-lever pivoted in said bushing with one end adapted to contact with the bottom of the angular plate, a rod secured to one end of the operating-lever, means to impart motion to said operating-lever whereby the angular plate is reciprocated.
- 30 2. In a spotting device for bowling-alleys, an operating-lever having one end turned at right angles, a bushing adapted to pivotally support said operating-lever, a plate having pins secured thereto contacting with the end of the operating-lever, a locking-lever secured to one end of the operating-lever, means to impart movement to said plate to force the spotting-pins above the surface of the alley

and to permit them to drop below by gravity, an elastic washer adapted to frictionally contact with the lever-rod for the purpose set forth.

3. In a pin-spotter for bowling-alleys, an operating-lever having one end turned at right angles, a locking-lever secured to one end, a bushing having enlarged ends with a contracted center portion forming a ring and adapted to pivotally support said operating-lever, a plate having spotting-pins secured thereto and adapted to fit loosely in corresponding apertures provided in the surface of the alley, means to force the ends of the spotting-pins above the alley-surface, means to permit them to drop below by gravity as described and set forth.

4. In a pin-spotting device, an operating-lever pivotally secured to the pit, one end of said operating-lever turned at right angles with the body portion, a plate, spotting-pins secured to said plate, a locking-lever to operate said lever whereby the plate carrying the pins is forced upward to make ends of the pins extend above the surface of the alley and to permit the plate to drop by gravity, a plate to hold the lever in position, a washer fitted to the locking-lever to frictionally hold it in place.

5. In a pin-spotting device, an operating-lever, a plate, a series of spotting-pins with the front pin made longer secured thereto, bowling-pins having apertures formed in the bottom, a locking-lever, means to force the spotting-pins below the surface, means to force the pins above the surface preparatory to setting the bowling-pins as described.

Signed at Mansfield, Ohio, this 26th day of March, 1906.

WALTER JAY TREMAN.
